UNITED STATES PATENT OFFICE.

ARTHUR A. HUTCHISON, OF HARRISBURG, PENNSYLVANIA.

SPARK INTENSIFIER.

Application filed December 31, 1921. Serial No. 526,275.

To all whom it may concern:

Be it known that I, ARTHUR A. HUTCHISON, a citizen of the United States, residing at Harrisburg, in the county of Dauphin and State of Pennsylvania, have invented new and useful Improvements in Spark Intensifiers, of which the following is a specification.

This invention relates to improvements in 10 spark intensifiers for internal combustion engines.

An object of the present invention is the provision of a spark intensifier which is simple and compact in construction and 15 which is provided with a novel form of sparking point, so arranged and held, that it cannot become accidentally displaced and thus interfere with the proper functioning of the device, the means employed for insuring prevention of displacement also providing means for holding in position a transparent cover, for a sight opening.

With the above and other objects in view, the invention further includes the following 25 novel features and details of construction, to be hereinafter more fully described, illustrated in the accompanying drawings and pointed out in the appended claims.

In the drawings:—

20 Figure 1 is a plan view of a spark intensifier constructed in accordance with the invention.

Figure 2 is an edge view of the same.

Figure 3 is a top plan view with the 35 clamping member removed.

Figure 4 is a central longitudinal sectional view of the device.

Figure 5 is a plan view of the blank from 40 which the clamping member is formed.

Figure 6 is a detail perspective view of one of the conductor plates.

Referring in detail to the drawings, wherein like characters of reference denote corresponding parts, the intensifier as shown comprises a body member which is formed of insulating material, preferably fiber, and includes a base plate 10 and plates 11 and 12 which are arranged upon the base plate in superimposed relation. The plates 10, 11 and 12 are preferably diamond shape in plan view and the two last mentioned plates are provided with aligned openings to form a centrally arranged sparking chamber 13. Secured between the plates 11 and 12, are 55 conductor plates 14 which are of triangular

formation so that their side edges will be flush with the side edges of the plates 11 and 12. Extending from the opposed edges of the plates 14 are spurs 15, whose adjacent ends are spaced apart to provide a spark 60 gap within the chamber 13.

Each of the plates 10, 11, 12 and 14 are provided with openings and when these plates are assembled, the openings register to permit of the passage of combined assembling and terminal eyes 16. The opposite edges of these eyes are bent outward into engagement with the plates 10 and 12 as indicated at 17 so that the plates are clamped together, while the openings provided by the 70 eyes form means for attachment to a spark plug terminal and a conductor terminal.

The top of the sparking chamber 13 is closed by a transparent member 18, preferably formed of mica and this transparent member is held in place by a clamping member 19. The clamping member is arranged transversely of the intensifier body and is provided with a centrally disposed offset portion 20 having a sight opening 21 therein. This offset portion 20 provides a space for the reception of the transparent member 18 so that the latter will be securely held against accidental displacement without providing undue pressure upon its edges, which 80 might crack or destroy the plate and thus render it useless. The clamping member 19 is provided with oppositely and radially extending arms 22, which are bent over the side edges and beneath the bottom of the intensifier body as shown so that the body portion of the clamping member forces or 85 clamps the intermediate portion of the plate 12 downwardly against the plate 11 and between the opposed edges of the conductor plates 14, as shown at 23, so that accidental pivotal movement of the conductor plates upon the eyes 16 is prevented. The spurs 15 which form the sparking points of the intensifier are thus rigidly and securely held in place so as to insure proper functioning 90 of the device. In addition, the plate 18 securely covers the sparking chamber 13 so that the gasoline or other highly explosive vapors will be prevented from entering the 95 sparking chamber.

The invention is susceptible of various changes in its form, proportions and minor details of construction and the right is herein reserved to make such changes as properly 100 105 110

fall within the scope of the appended claims.

Having described the invention what is claimed is:—

1. A spark intensifier comprising a substantially diamond shaped body formed of superimposed layers of insulating material and comprising a base plate, plates positioned upon the base plate and having centrally arranged registering openings therein
- 10 to provide a sparking chamber, substantially triangular shaped conductor plates positioned between the insulating plates, spurs extending from one edge of each of the conductor plates and projecting into the sparking chamber to provide a spark gap, combined assembling and terminal eyelets extending through the insulating plates and conductor plates and a transparent cover for the sparking chamber.
- 15 2. A spark intensifier comprising a substantially diamond shaped body formed of superimposed layers of insulating material

and comprising a base plate, plates positioned upon the base plate and having centrally arranged openings therein to provide 25 a sparking chamber, substantially triangular shaped conductor plates positioned between the insulating plates, spurs extending from one edge of each of the conductor plates and projecting into the sparking chamber 30 to provide a spark gap, combined assembling and terminal eyelets extending through the insulating plates and conductor plates, an apertured clamping member extending across the body and clamping the intermediate 35 portion of the topmost insulating plate upon the next adjacent insulating plate to hold the conductor plates against accidental pivotal movement and a transparent cover positioned beneath the apertured clamping 40 member.

In testimony whereof I affix my signature.

ARTHUR A. HUTCHISON.
